CLEMENT OLHABER, OF CINCINNATI, OHIO, AND NICHOLAS S. VEDDER, OF TROY, NEW YORK, ASSIGNORS TO WOODROW, MEARS & CO., OF CINCINNATI, OHIO.

Design No. 2,732, dated August 6, 1867.

DESIGN FOR A COOK'S STOVE.

The Schedule referred to in these Letters Patent and making part of the same.

TO ALL WHOM IT MAY CONCERN:

Be it known that we, CLEMENT OLHABER, of Cincinnati, Ohio, and NICHOLAS S. VEDDER, of Troy, New York, have jointly invented or produced a new and original Design for a Cooking-Stove, of which the following is a full and exact description, reference being had to the accompanying photographs, in which—

Figure 1 is an angular view, and

Figure 2 a side view of a cooking-stove having our said design.

The distinguishing features of this design consist of the particular compound centre ornaments *a a* and border ornaments *b b*, arranged on the doors *c c*, the scroll-work or vine-like ornaments *d d*, arranged on the upper portion of the side plate *E*, the word "telegraph" on the panel of the inclined upper front doors *F F*, and the letter "T" on the ornamented foot *G*, all shaped so as to appear as represented by the accompanying photographs.

What we claim as our invention or production, and desire to secure by Letters Patent, is—

A design for a cooking-stove having the distinguishing features herein set forth and shown by the accompanying photographs.

CLEMENT OLHABER,
NICHOLAS S. VEDDER.
